Primary Examiner — Dana L Meyrow(74) *Attorney, Agent, or Firm* — Fross Zelnick Lehrman & Zissu, P.C.; Charles T. J. Weigell, Esq.(57) **CLAIM**

The ornamental design for a bottle, as shown and described.

DESCRIPTION

FIG. 1 is a front elevation view of a bottle showing my new design, the left side, right side and rear elevation views being identical;

FIG. 2 is a top perspective view thereof;

FIG. 3 is a top plan view thereof, the opposing side details seen through the transparent material being omitted for ease of understanding; and,

FIG. 4 is a bottom plan view thereof.

The evenly-dashed broken lines in the drawings showing the bottle pour spout, top portion of the bottle neck, and the bottom surface recess illustrate the portions of the design that form no part of the claim. The short dash-long dash broken lines in the drawings define the bounds of the claim and form no part thereof.
